MAGNETIC TAPE PLAY-BACK UNIT

Yutaka Kigoshi, Fujisawa-shi, Japan, assignor to Pioneer Kabushiki Kaisha (also trading as Pioneer Electronic Corporation), Tokyo-to, Japan, a joint-stock company of Japan

Filed May 3, 1966, Ser. No. 2,153

Term of patent 3½ years

(Cl. D26—14)

FIG. 1

FIG. 2

FIG. 3.

FIG. 4.

FIG. 5

FIG. 6

FIG. 7

FIG. 8

FIG. 1 is a front elevational view of a magnetic tape play-back unit showing my new design;

FIG. 2 is a rear elevational view thereof;

FIG. 3 is a side elevational view seen from the right of a magnetic tape play-back unit;

FIG. 4 is a side elevational view seen from the left thereof;

FIG. 5 is a top plan view thereof;

FIG. 6 is a bottom view thereof;

FIG. 7 is a top perspective view thereof;

FIG. 8 is a perspective view thereof, with a cartridge of recorded tape illustrated in broken lines for illustrative purposes only.

The dominant features of my design reside in the portions shown in full lines.

I claim:

The ornamental design for a magnetic tape play-back unit, as shown and described.
